UNITED STATES PATENT OFFICE

2,436,292

CYLINDER HOLDER

Armand De Mott, Fords, N. J., assignor to Amity Manufacturing Corp., Perth Amboy, N. J., a corporation of New Jersey

Application October 2, 1946, Serial No. 700,729

1 Claim. (Cl. 248—311)

1

The holder of my invention is especially adapted for the holding of elongated cylinders such as fire extinguisher cylinders, securely in partly exposed position, under tension, and, at the same time, to permit of the instantaneous removal of the cylinders therefrom when desired.

An embodiment of a structure employing my invention is shown in the accompanying drawings and described in detail in the ensuing specification. This embodiment is merely by way of example; my invention is not limited thereto but includes all other forms which would come within the scope of the appended claims. In the drawings,

Fig. 1 is a vertical sectional view of a cylinder holder embodying my invention.

Fig. 2 is an elevational view thereof; taken on line 2—2 of Fig. 1, and

Fig. 3 is a view similar to Fig. 1, showing a fire extinguisher cylinder positioned in the holder of my invention.

As shown in the drawings, the holder of my invention comprises a member 10 of generally U-shaped cross-section, open at the upper end 11 thereof and closed at the lower end 12 thereof, said lower end 12 being rounded and being provided with a medial boss 13 on which the nozzle end of the cylinder 22 is supported and is thus sealed from the atmosphere. The holder 10 is provided with lugs 14 and 15 at the upper and lower ends thereof, said lugs having apertures 16 and 16' for the reception of screws or like holding means S to fasten the holder to a wall or other support W. The cylinder is provided with spring means to maintain the cylinder under tension therein and centered on the boss 13. As shown in Fig. 1, said spring means comprises a spring member 17 fixed at one end to the holder by means of a rivet 18 or the like, the spring being preferably bowed, as at 19 to normally project into the holder. The lower end of the holder is provided with a medial rib 20 which is connected with the rear wall 24 of the holder and with the depending lug 15, and which thus serves to reinforce the lower end of the holder.

The holder may be made of metal or plastic or of a combination of such materials or of any other desired or convenient material, the parts being so proportioned that the internal diameter D of the holder will be slightly larger than the external diameter of the cylinder 22 to be held therein.

As will be noted from Fig. 3, the cylinder 22

2

upon being positioned within the holder, flattens the bowed portion 19 of spring 17, thereby maintaining the cylinder tightly within the holder. The nozzle end 23 of the cylinder 22 rests on the medial boss 13 at the lower end of the holder so that the nozzle end of the cylinder is substantially sealed from the atmosphere, precluding the possibility of contamination of the nozzle end of the cylinder and of the discharge aperture thereof.

10 It will be apparent from Fig. 3 that on inserting the cylinder 22 into the holder, the cylinder automatically aligns itself onto the medial boss 13 and is held tightly or under tension in the holder with the exposed end of the cylinder projecting above the open end 11 of the holder in position for rapid and effortless removal of the cylinder when so desired.

While I have described the holder 10 as used for the reception of the fire extinguisher cylinder 22, 20 it will be apparent from the foregoing description that the same may be used for the holding of other objects of similar kind in the same fashion.

I have shown in the drawings and described in the above specification, a convenient form of 25 structure embodying my invention; it will be apparent from such disclosure that the invention is capable of many modifications without departing from the spirit and scope thereof, as set forth in the appended claim.

30 Having thus described my invention what I claim as new and desire to secure by Letters Patent, is:

A holder for a cylinder having a nozzle, said holder comprising a member of generally U-shaped cross-sectional outline having a rounded, closed lower end and an open upper end, a medial boss in the lower end of said holder on which the nozzle of the cylinder may rest, and spring means secured to the holder and projecting thereinto 40 to hold the cylinder positioned therein tightly on the boss.

ARMAND DE MOTT.
